UNITED STATES PATENT OFFICE.

ROBERT CORNELY, OF PARIS, FRANCE.

HEMSTITCH SEWING AND EMBROIDERING MACHINE.

1,090,136.

Specification of Letters Patent. Patented Mar. 17, 1914.

Application filed April 15, 1913. Serial No. 761,281.

To all whom it may concern:

Be it known that I, ROBERT CORNELY, a citizen of the United States, resident of Paris, France, have invented a new and useful Improvement in Hemstitch Sewing and Embroidering Machines, which is fully set forth in the following specification.

The present invention relates to improvements in hemstitch sewing and embroidering machines in which the formation of the seam is obtained by the coöperation of two needles having a combined vertical and lateral displacement, working in conjunction with a piercer which pierces the material. But since in these machines the effect of the seams depends not only on the amplitude of the stroke of the lateral or spreading movement of the needles, but also on the distance at which the needles perform their lateral or spreading movement from each other, (which lateral distance determines the width between the two inner rows of seams of the hemstitch), these machines must be provided with means not only for regulating the stroke of the spreading movement of the needles, but also for controlling the distance at which the needles perform their oscillating or spreading motion from each other, by means of regulating devices which permit an exact adjustment and which will not get out of adjustment at high speeds of the machine, which result has been obtained heretofore only by delicate and unreliable devices. Further it is necessary in hemstitch embroidery machines with universal feed that the operator shall be able to interrupt at will the feed of the material while the machine continues working, in order to produce angular seams or small curves or circles.

Finally, an objection heretofore existing in machines working with pivoted needle-bars, resided in the fact that the transmission of the turning movement of the crank handle which governs the direction of the feed upon the needle-bars was obtained by means of different gears or transmissions upon the upper and lower parts of these needle-bars, so that as soon as a certain wear or play took place between these gears or transmissions, the upper and under parts of these needle-bars no longer turned strictly together, thus occasioning strain and bending of the needle-bars and of their joints and undue wear of the machine.

The object of the present invention is to

obviate these inconveniences. By way of example, one expression of the inventive idea as applied to a universal feed embroidering machine is illustrated in the accompanying drawings.

Figure 1 is a side view partly in section; Fig. 2 is a front view; Figs. 3, 4, 5, 6, 7, 10, 11 and 12 are details hereafter to be referred to, and Figs. 8 and 9 show the transmission of the turning movement of the crank handle which governs the direction of the feed, upon the central tube of the needle-bars, as well as the provisions for interrupting at will the feed of the material, while the stitch forming elements of the machine continue working.

In the present example the lateral displacement or spreading of the needle-bars is obtained by the up and down motion of a wedge-shaped part, the inclined surfaces of which act against corresponding inclined surfaces of slides counterpressed by springs, said slides being provided with pivoted guides through which pass the needle-bars. In order to permit the adjustment of the distance between the two inner rows of the hem-seam, this wedge-shaped part has, in the present invention, been secured adjustably in its height upon a vertically moving sleeve or slide and according to the height at which it is adjusted, the constant distance between the two inner rows for each seam to be produced, will be increased or decreased. Because it is very important to adjust the position of the needle spreading device with great precision and also very important that after its adjustment it will not become out of adjustment during the work, this wedge-shaped part has in the present invention been provided in such manner upon the up and down moving slide or sleeve, that its position is adjusted by a regulating device provided with an incline which acts against a corresponding incline of the wedge-shaped part and since during the work of the machine the resistance acting upon this wedge shaped part is transmitted upon the incline of the regulating device, the angle of which latter incline is very small only, it will be clear that after having been screwed in position, a loss of adjustment need not be feared.

Main shaft 1 of the machine (Fig. 1) is provided with a gear wheel 2 which drives a gear wheel 3 three times larger mounted on a shaft 4 provided with a cam 5 which

oscillates a bell crank lever 7 pivoted at 6. The under arm of this bell crank lever 7 is provided with a slot 8 in which engages a bolt 9 which at the same time engages in a 5 corresponding slot of lever 11 pivoted at 10; as shown and described in United States Letters Patent No. 944,599 of December 28, 1909, according to the position of bolt 9 in slot 8, the oscillation of lever 11 can be regulated from zero to a maximum. The other 10 end of lever 11 transmits an oscillating motion to slide 12 which is provided with a fork 13 which engages in a slot of sleeve 14 which thus receives an up and down motion 15 upon the central tube 29. A wedge-shaped part 15 (Fig. 4) is provided adjustably upon this sleeve 14 and secured in position by a screw 16 which passes through a slot of said wedge-shaped part 15. Upon sleeve 14 is 20 mounted a movable adjustment device 18 provided with an incline 17 which bears against the upper part of the wedge-shaped part 15 provided with a corresponding incline. It is clear that according to the position 25 of this regulating device 17-18, which may be provided with divisions *a*, *b*, *c*, allowing a very exact adjustment, the position of said wedge-shaped part 15 can be regulated with the greatest precision and main- 30 tained in place by screw 19.

In the downward motion of the wedge-shaped part 15, its two inclined faces (see Figs. 4 and 6, the latter being a horizontal section on line A—B Fig. 4,) act against corresponding inclines 20 and 21 of slides 22 and 23 which are counterpressed by springs 61 and 62; with said slides 22 and 23 there are connected in a pivotal manner two guides 25 and 26 through which pass the 35 lower ends of the needle-bars 27 and 28. As shown in Fig. 7 these guides 25 and 26 are provided with spindles which are revoluble within sockets in the slides 22 and 23 in order to follow all angular displacements of 40 the needle-bars 27 and 28 in their oscillation. It will be seen from Fig. 10 that this adjustment device 17-18 can equally well be used in combination with machines in which the 45 spreading of the needles is obtained by means of pins 67 and 68 upon the sleeve 14 engaging in inclined slots 69 and 70 upon slides 71 and 72. For this purpose it is merely necessary to arrange the arms 73 and 74 carrying said pins 67 and 68 upon 50 a slide 75 which is adjustable by the regulating device 17-18 in the manner above described.

In universal feed embroidering machines it is necessary that the needle-bars as well 55 as the parts depending from the central tube 29 of the machine shall turn exactly together with said central tube in conformity with the crank handle 30 (Fig. 8) which governs the direction of the feed of the material. When these machines were provided

with pivoted needle-bars there was heretofore the inconvenience that the upper ends of the needle-bars were pivoted to an upwardly and downwardly moving sleeve 31 (Figs. 1 and 9) which received its turning 70 motion indirectly from the central tube 29 by means of a certain number of gears 63, 64, 65, 66 and intermediate transmissions, while the lower ends of these needle-bars were guided in parts depending directly of 75 said central tube 29, the consequence of this was that as soon as a certain wear or play had taken place in said gears or said transmissions, the upper and lower ends of the needle-bars no longer turned strictly together, thus occasioning strains and deformations of the needle-bars and of their pivots and wear upon the machine. In order to obviate these inconveniences, in the present improvement the needle-bars 27 and 28 are 80 not pivoted to sleeve 31 (Figs. 1 and 9) but on the contrary, they are fixed rigidly on said sleeve 31 and at the same time a sleeve 32 is secured within central tube 29 and is provided with passages within which the 85 upper parts of the needle-bars 27 and 28 are guided, while the hinges 33 and 34 of the needle-bars 27 and 28 are provided underneath said sleeve 32, and since the lower ends of these needle-bars are guided at 25 and 90 26 in slides 22 and 23 (Figs. 4, 5 and 6) provided directly on this one and same central tube 29, it is clear that the upper and lower ends of these needle-bars 27 and 28 will turn for their full length directly together with 95 the central tube 29 so that deformation of the needle-bars or of their pivots will be obviated. In these machines it is also necessary for the production of angular seams or small turnings or circles, that the operator 100 may at will interrupt the feed of the material while the stitch forming mechanisms of the machine continue to perform their work. In the present invention this is obtained in the following manner: The above 110 described shaft 4 (Figs. 1 and 2) is provided with a cam 35 which engages one arm of a lever 36 connected to slide 38, thus vertically moving the latter against the tension of a spring 37. This slide 38 operates the feed 115 of the material in the manner well known in universal feed embroidering machines. In order to interrupt the action of this lever 36 at the will of the operator and of course at the same time to interrupt the feed of 120 the material, an arm 39 is pivoted at 40 and according to the position of this arm 39, the lever 36 is either free to swing (Figs. 1 and 2) or blocked against movement (Fig. 3). The arm 39 may be controlled for example 125 from the crank handle 30 (Fig. 8) which for this purpose is provided with a lever 41 upon which the operator acts at the required moment; its displacement is transmitted to the arm 39 by means of lever 42, 130

rod 43, lever 44, rod 45, bell crank lever 46 and rod 47 under the counterpressure of a suitably arranged spring. The arm 39 may also be controlled by a lever 48 (Figs. 1 and 5 8) having an operating cord and ring 49 which can be operated by the hand of the operator which guides the material upon the table. Again, the arm 39 may 10 be operated by the foot or knee of the operator by means of a prolongation 50 (Fig. 8) of rod 45, this being suitably connected to a treadle or a knee lever. The up and down motion of the piercer 53 (Figs. 1 and 2) which is provided between the needles 51 15 and 52 is obtained from the main shaft 1 of the machine by means of a cam 54, bell crank lever 55, rod 56 and slide 57, from which a fork 58 transmits an up and down motion to the sleeve 59 which carries the 20 rod 60 of the piercer 53.

Figs. 11 and 12 show the manner in which a thin and flat ribbon 76 may be sewn to the material by the spreading needles 51 and 52 and pierced by the piercer. This is obtained 25 by providing guide 77 within the presser foot 78, said guide 77 being provided with a slot 79 corresponding in its dimensions to the width and thickness of the ribbon and a vertical passage for the needles and the 30 piercer. By means of this arrangement a ribbon or the like may be secured to the material, said ribbon being at the same time embroidered with a hem stitch.

While for the purpose of illustration there 35 has herein been shown and described in considerable detail one expression of the inventive idea, it is to be understood that the invention is not limited to the construction shown, but that the inventive idea is susceptible of various mechanical embodiments 40 conforming to the definition of the invention set forth in the appended claims.

Claims.

1. In a device of the character described, 45 the combination of a plurality of needle bars, means for reciprocating the same, a vertically-moving member, means for operating the same, means for spreading said needle bars mounted upon said member, and 50 means carried by said member for adjusting the position of said spreading means on said member.

2. In a device of the character described, 55 the combination of a plurality of needle bars, means for reciprocating the same, a vertically-moving member, means for operating the same, means for spreading said needle bars mounted upon said member, and an adjustable regulating device carried 60 by said member and engaging said spreading means.

3. In a device of the character described, 65 the combination of a plurality of needles, means for reciprocating the same, a vertically-moving member, means for operating

the same, a device mounted upon said member for spreading said needles, said device being provided with an incline or cam surface, and an adjustable regulating device acting on said spreading device and provided 70 with a corresponding incline or cam surface, said surfaces engaging one another.

4. In a device of the character described, 75 the combination of a plurality of needles, means for reciprocating the same, a vertically-moving member, means for operating the same, a device mounted upon said member for spreading said needles, said device being provided with an incline or cam surface, and an adjustable regulating device 80 carried by said member and provided with a corresponding incline or cam surface, said surfaces engaging one another.

5. In a device of the character described, 85 the combination of a plurality of reciprocating needle bars, slides through which said bars pass, and a needle spreading device comprising a reciprocating support, a wedge-shaped member mounted thereon, the inclined faces of which act against said 90 slides to spread the needles, and means to adjust said wedge member on its support to vary the spread of the needles.

6. In a device of the character described, 95 the combination of reciprocating needle bars, spring-pressed slides through which said bars pass, a vertically-moving member, a wedge-shaped needle-spreading device carried by said member and having inclines bearing on said slides, and means carried by 100 said member for adjusting the position of said device.

7. In a device of the character described, 105 the combination of a central tube, a plurality of needle bars arranged in said tube, means for reciprocating said bars, a sleeve secured in the upper end of said tube and having passages through which the needle 110 bars pass, joints being provided in said needle bars below said sleeve, and means for spreading the lower ends of said needle bars.

8. In a device of the character described, 115 the combination of a plurality of needle bars each in two sections pivoted together, means for reciprocating said bars, a central tube through which said bars pass, means carried by the upper end of said tube and engaging the upper part of each of said bars, movable elements mounted on said 120 tube to which the lower ends of said bars are connected, means operating said elements to spread said bars, and means for rotating said central tube whereby the upper and lower sections of each bar receive 125 their turning movement directly from said tube.

9. In a device of the character described, 130 the combination of a plurality of needle bars each in two sections pivoted together,

means for reciprocating said bars, a central tube through which said bars pass, a sleeve carried in the upper end of said tube, said sleeve being provided with passages through which the upper sections of said bars project, slides mounted on the lower end of said tube, said slides engaging the lower ends of said bars, means operating said slides to spread said bars, and means for rotating said central tube whereby the upper

and lower sections of each bar receive their turning movement directly from said tube.

In testimony whereof I have signed this specification in the presence of two subscribing witnesses.

ROBERT CORNELY.
